UNITED STATES PATENT OFFICE.

JOHN ROBES AND CLARENCE D. COMPTON, OF NEW YORK, N. Y.

WRENCH.

1,334,261.

Specification of Letters Patent. Patented Mar. 16, 1920.

Application filed May 16, 1919. Serial No. 297,695.

To all whom it may concern:

Be it known that we, JOHN ROBES, a citizen of Greece, and CLARENCE D. COMPTON, a citizen of the United States, both residents of the city of New York, borough of Manhattan, in the county and State of New York, have invented a new and Improved Wrench, of which the following is a full, clear, and exact description.

This invention relates to a wrench, and aims more particularly to provide a device of this nature which shall be peculiarly adapted for use in connection with toggle bolts and which will greatly facilitate their application to their applied position.

A further object of this invention is the provision of a wrench which will include construction permitting of the shearing off of the bolt when the device is once applied.

A still further object of this invention is to provide a wrench of the socket type which will readily engage the means used to retain a toggle bolt in applied position, so that the fastening of the bolt to a wall or other supporting structure is a comparatively easy matter.

Another object of the invention is the provision of restraining means for preventing the disengagement of the part of the toggle bolt to be tightened up with respect to the wrench.

A still further object of the invention is the provision of a wrench of this type with a removable socket, so that the same may accommodate various sizes of toggle bolts, together with the means used to apply them to their final position.

Another object of the invention is to provide a socket which may be reversed, so as to accommodate various sizes of bolt-retaining nuts, that it may not be necessary, in most instances, to apply an entirely different socket.

A final object of this invention is the provision of a wrench of this type which shall be extremely simple in construction and, consequently, economical in manufacture.

Reference is had to the attached sheet of drawings which illustrate one practical embodiment of our invention, and in which—

Figure 1 is a sectional front elevation of our improved wrench;

Fig. 2 is a sectional side view of the wrench with the handle removed from its body portion; and

Figs. 3, 4 and 5 are plan views of the various heads which may be removably attached to the body of the wrench so as to accommodate various sizes of toggle bolts. 60

In all these views like reference numerals designate similar parts, and the reference numeral 1 indicates a handle adapted to be secured to a shank 2 which is formed with a bore 3. The lower end of the shank 2 is 65 formed with screw threads, as indicated by the reference numeral 4. Engaging the screw threads, and retained by them in applied position, is a socket 5 which is also formed with a bore the ends of which are 70 interiorly screw threaded so as to engage the screw threads 4, as before stated. The upper and lower edges of the socket 5 are formed with grooves, such as 6, of varying sizes, so as to be adaptable for varying 75 sizes of nuts, such as 7, which are mounted upon the screw-threaded bolt 8 of the toggle bolt. These grooves 6 may further be formed with notches 6', which will permit of their being adapted to a still greater 80 range of varying sizes of nuts.

The socket 5 is formed with an opening, such as 9, which is adapted to have projecting within it a stud 10 integral with or secured to a spring arm 11 terminating in 85 a collar 12 slidably mounted upon the shank 2, and the socket 5 is formed with a groove 11' in which the spring arm 11 seats. The lower end of the arm 11 terminates in a right-angled projection 13 which engages 90 the under side of the nut 7.

In operation it will be noted that the socket 5 may have either of its ends applied to the shank 2 so as to accommodate varying sizes of nuts 7. Assuming now 95 that the toggle bolt has been inserted through an opening and is being retained therein by means of a nut, such as 7, it will be perfectly obvious that the shank of the bolt 8 will be presented upwardly within 100 the bore 3 and that one of the grooves 6 will engage the side walls of the nut and turn the same with the wrench handle. During this operation the right-angled projection 13 will, as aforesaid, engage the 105 underside of the nut 7 and prevent any displacement of the screw with respect to the socket 5.

The proper positioning of this right-angled projection is secured by means of the 110 stud 10, which will ride along the outer surface of the socket 5 until the same enters

into the opening 9, whereupon the spring arm 11 will snap the stud 10 into such opening, consequently, carrying the right-angled projection 13 to the position indicated in Fig. 2.

Should it be desired to accommodate a different sized nut than the nut 7, it will be seen that this can be readily done by simply reversing the socket 5 so as to prevent the opposite groove 6 to act upon the nut 7.

Finally, it will be perceived that when the nut 7 has been properly positioned upon the bolt 8, this bolt may be broken off at the proper length by primarily tightening the nut 7 beyond the point at which it is illustrated in the drawings, so that the bolt 8 will extend far into the bore of the shank 3. The shank may now be rocked from one extreme to the other, which will result in a weakening of the bolt at the point of bending and the subsequent breakage of the same at this point.

It will be appreciated that various modifications of this device as illustrated may be made without in the least departing from the scope of our invention.

Having thus described our invention, what we desire to claim is:

1. A wrench, including a shank formed with a bore, a head, including a cylindrical

body open at the ends and having such ends formed with grooves, providing work-engaging faces, such head being removably and reversibly secured to the shank.

2. A wrench, including a shank, a work-engaging face applied to the lower end of such shank, work-retaining means, including a collar, slidably mounted upon such shank, and a spring arm projecting downwardly from such collar, the lower end of such arm being bent inwardly and projecting below the work-engaging face whereby to retain the work in engagement therewith.

3. A wrench, including a shank, a work-engaging head secured to the lower end of such shank, such work-engaging head being formed with a groove in its outer face and an opening projecting from such groove inwardly into the head, a collar slidably mounted upon such shank, and a spring arm terminating in an inwardly-projecting end portion extending below the work-engaging face for retaining the same in engagement with the head, such arm being adapted to seat within the groove and being provided with a stud adapted to engage the opening in such head when the lower end of the arm is in applied position.

JOHN ROBUS.
CLARENCE D. COMPTON.
